UNITED STATES PATENT OFFICE.

WILLIS E. BOWEN, OF ROCHESTER, NEW YORK.

GAME DEVICE.

SPECIFICATION forming part of Letters Patent No. 783,607, dated February 28, 1905.

Application filed March 2, 1904. Serial No. 196,242.

To all whom it may concern:

Be it known that I, WILLIS E. BOWEN, a citizen of the United States, and a resident of Rochester, in the county of Monroe and State 5 of New York, have invented certain new and useful Improvements in Game Devices, of which the following is a specification.

This invention relates to game devices.

In the drawings, Figure 1 is a vertical section on the line 1 1 of Fig. 2, and Fig. 2 is a cross-section on the line 2 2 of Fig. 1.

The case consists of a bottom piece 1 of transparent material, and a transparent cover 2, of glass, celluloid, or other suitable material, fastened upon said bottom piece and comprising a cylindrical portion and an end that is rounded or otherwise shaped. The device also includes two cups 3 3, that are contained within the transparent walls of the case and 20 that face in the same direction. There is a space upon the bottom of the case and around

the cups for two bodies or balls 4 4. The two cups are separated from each other by about the diameter of a ball and are closely contiguous to opposite sides of the cylindrical 25 case within which the balls and cups are contained. By dexterous management the two bodies or balls may be placed in the cups.

What I claim is—

As an improved article of manufacture a 30 game device comprising a transparent, elongated cylindrical casing closed at both ends, horizontal cups secured at opposite points to the inner wall of the casing between the ends thereof and projecting toward the center of 35 the casing, and a loose playing-piece for every cup, in the bottom of said casing.

WILLIS E. BOWEN.
